CHARGE FORMING AND POSITIONING APPARATUS.

1,401,687.

Specification of Letters Patent. Patented Dec. 27, 1921.

Application filed May 23, 1919. Serial No. 299,286.

To all whom it may concern:

Be it known that we, MATHIAS FOGDE and LAWRENCE P. SOUTHWICK, respectively a subject of the Government of Russia and a citizen of the United States, residing at Richmond, in the county of Henrico and State of Virginia, have invented new and useful Improvements in Charge Forming and Positioning Apparatus, of which the following is a specification.

This invention relates to improvements in charge forming and positioning apparatus, and pertains more particularly to apparatus operative to automatically produce a charge of multi-unit character for work-performing apparatus.

While the invention is not limited in use to charges of multi-unit character—being applicable for use in connection with single units—it is especially adapted for multi-unit service and particularly where the operations of the work-performing apparatus are of the nature of "gang" operations. Nor is the invention limited to use in connection with any particular type of work-performing apparatus or character of unit.

For the purpose of explaining the invention, however, we have shown it as employed in the production of charges formed of individual packages, such for instance as cigarette packages, the work to be performed on the charge being that of applying the usual revenue stamp to each of the units of the charge. For instance, the apparatus may be employed in producing the charges for the apparatus disclosed in the patent granted to us October 23, 1917, No. 1,244,438, an apparatus designed to locate a succession of units—forming a charge—at predetermined points relative to stamp-applying mechanism, the operation of which serves to provide a stamp individually to each of the units of the charge, disclosure of the patent being designed to employ a charge of ten units to which a corresponding number of stamps are applied concurrently.

As will be understood, the presentation of a charge formed of a number of units of this type to a mechanism operative concurrently on all of the units requires that the units be presented concurrently rather than successively in order that the apparatus operation be not unduly delayed; in

other words, that the units of the charge be presented in a manner similar to that of a single unit, in order that the normal cycle of operation of the work-performing apparatus may not be effected in such manner as to decrease the capacity of the apparatus. Obviously, these conditions present a number of problems of maintaining the supply of units for the formation of charges, since each charge takes from the supply a number of units equal to the number contained in the charge—ten, in the particular apparatus referred to.

In addition, units of the type indicated—cigarette boxes for instance—are of dimensions such as to make it more or less difficult to maintain the supply owing to the space requirements where the attempt is made to position each unit in a charge in such manner as to permit the application of the stamp onto an end of the unit and especially where the stamp extends onto both sides of the unit when applied, an arrangement which practically requires that the unit be stood on an end during the stamp applying operation. And the difficulties present will be further appreciated from the fact that stamping mechanism of this general type has a capacity such as will take care of the product of a number of machines operative to produce the supply itself.

The present invention is designed to meet these problems and to make possible the forming and positioning of a multi-unit charge at the presenting mechanism of the work-performing apparatus in a simple and efficient manner and in such a way as to permit the supply to be maintained without the use of special care or expert assistance.

These ends are obtained by providing the supply in the form of superposed rows of units arranged in flatwise contact, the units having their direction of length extending more or less horizontal with one end in advance, each row containing a number of units corresponding to the number adapted to produce the charge. This permits of the use of a suitable filling tray within which the operator can readily locate the units in such rows, obtaining the supply therefor from a supply mechanism, the filling tray having a false bottom which enables the operator to shift the contents of his tray

onto the units previously located in the charge reservoir.

The charge reservoir is located relative to a suitable presenting mechanism in such way 5 that advance of the lower row of the reservoir carries the units of that row in the direction of the position of the presenting means, and the structure is so arranged that each unit is shifted from the horizontal to 10 the vertical during this advance movement, this being provided by what may be considered a stage operation, although the mechanism employed produces the two-stage operation during a single cycle of its movement. 15 The mechanism thus locates all of the units in their proper positions relative to each other, so that the presenting mechanism can advance them bodily and concurrently as a charge to the work-performing apparatus. 20 To this and other ends, the nature of which will be readily understood as the invention is hereinafter disclosed, said invention consists in the improved construction and combination of parts hereinafter more 25 fully described, illustrated in the accompanying drawings, and more particularly pointed out in the appended claims.

In the accompanying drawings, in which similar reference characters represent similar parts in each of the views,

Figure 1 is a vertical section taken through a simple form of apparatus adapted for use for the purpose indicated, the view showing the parts at an intermediate stage of the 35 general operation.

Fig. 2 is a similar view showing the parts in a different position.

Fig. 3 is a sectional plan view, the section plane being just above and parallel to the 40 plunger 13.

Fig. 4 is a perspective view of a filling tray.

Fig. 5 is a fragmentary perspective section of the unit advancing element.

45 A indicates a frame element which may be individual to the structure of the present invention, but which is preferably a part of the general frame work of the work-performing apparatus, the frame element having suitable guides on its upper face adapted to control the movement of a presenting element *a* which may be of any suitable design and which may include a vertically extending finger or other element *a'*. Member *a* may, for instance, be in the form of an endless belt intermittently driven with a suitable number of elements *a'* properly positioned thereon, or said member may be in the form of a reciprocating structure.

60 Finger *a* is adapted to travel in what may be considered a trough formed by front and rear walls 10 and 11 respectively, the front wall being of a suitable design, the rear wall 11, however, having a more or less special 65 configuration, in that its inner face extends

on more than a single plane on a vertical section of the wall, the upper portion of the wall, indicated at 11^a, being shown as inclined outwardly relative to the major portion of the remainder of the wall which extends substantially in a vertical plane.

The reservoir for the units is indicated at 12 being supported on frame A in suitable manner and preferably arranged slightly inclined to the vertical, the upper end projecting forward. The frame of the reservoir may be of any suitable structural formation with the front wall closed and the rear wall open at a point removed from the bottom of the reservoir, the latter having a 75 suitable plate 12^a secured at the rear at the bottom of the reservoir so that this plate and the front wall will provide a chute-like formation at the bottom of the reservoir and of a depth sufficient to accommodate several 80 rows—as for instance, four—of the units. The bottom of the receptacle is provided by a plate 12^b, and both the front and the rear walls of the reservoir are cut away adjacent plate 12^b, a distance substantially equal to 85 or slightly in excess of the thickness of a unit, as shown for instance in Fig. 2.

Plate 12^b extends forwardly beyond the face of the reservoir and to a position adjacent wall 11, the upper face of the plate being preferably a slight distance above the top plane of said wall, thus providing a support for an advancing unit and at the same time permitting the delivery of the unit from the plate onto the inclined face 11^a 100 of the wall. The openings in the front and rear walls of the reservoir have a length not less than the total length of the number of units which are to be concurrently delivered.

105 As heretofore set forth, the charge is formed by advancing the lower row of units from the reservoir, and this action is obtained by the use of an element 13—which may be considered as a plunger—and which 110 may be of any desired construction, it being preferred, however, to have a length sufficient to provide a face active on each of the units of the lower row. In the particular structure disclosed, this element is shown 115 as in the form of a plate, the advance edge of which is preferably inclined rearwardly toward the top plane of the plate; this inclination may be provided by a straight or a curved surface as may be found desirable, 120 the arrangement being preferably such, however, that a lower portion of the plate be active in advancing the units, this arrangement being preferred for a purpose presently described. The plate may be mounted in any suitable manner as, for instance, in guides 12^c, and is adapted to be reciprocated in the direction of advance of the units. This reciprocating action may be provided in any suitable manner, the drawings indi- 125 130

cating a suitable member 14 secured to the under face of the plate 13 and mounted on one or more guides 15. Member 14 is provided with an elongated slot 16 within which 5 a projection—which may be in the form of a roller 16^a—carried by an arm 17 operates, said arm being carried by a shaft 17^a rotatable in suitable manner from a suitable source. As shaft 17^a rotates, the pivotal 10 movement of arm 17 causes member 13 to reciprocate back and forth over the top of plate 12^b.

Fig. 2 indicates the position of member 13 at the beginning of its advancing movement, it being seen that the advance portion 15 of said member contacts with each of the units contained in the lower row of the reservoir; while but a portion of the member is in contact with the unit, it will be understood 20 that the latter will be advanced in a straight path by reason of the fact that the superposed rows will tend to prevent the units of the lower rows of being raised from off of plate 12^b. Therefore, as member 13 25 advances, the lower row of units is advanced correspondingly, the result being that the units will be advanced to project beyond the forward face of plate 12^b, and when the amount of projection has reached a point 30 where the greater portion of the weight of a unit is unsupported by plate 12^b, the preponderance of weight will cause each unit to tend to fall off of the plate. This "falling off" action is permitted by reason of the 35 particular configuration of the advance face of member 13, it being readily understood that the receding face formation will freely permit the rear end of the unit to shift vertically at this time although member 13 is 40 continuing its advancing movement. As a result, the units change their direction from the approximate horizontal to the inclined position shown in full lines in Fig. 1, resting upon the inclined face 11^a, and being 45 held from dropping into vertical position by reason of contact with the inner face of wall 10 on the opposite side of the trough. As, however, member 13 continues its advance, the advance face of the member again 50 becomes active on the canted units and pushes the rear portions of the units forwardly by reason of contact with the under side of the unit, the result being that a point is reached where the support provided by wall 10 becomes ineffective and the 55 units drop onto the positioning element *a* with the direction of length of the unit extending vertically as in dotted lines in Fig. 1.

60 While these movements of the unit have served to change its position from the approximate horizontal to the vertical, the movements have all been in the same vertical plane, with the result that the close relation 65 of adjacent units in the reservoir is main-

tained when delivered to the presenting element, so that finger *a'* may be positioned in close proximity to the path of travel of the unit with which it contacts during the presenting operation without liability of 70 preventing the free positioning of the unit. Hence, the positions of the units relative to each other is practically maintained and assurance will be had that the units of the charge will be located in their proper positions in the work-performing apparatus by 75 the advancing movements of the presenting mechanism.

As will be readily understood, the advance of member 13 places it as the temporary support of the remainder of the units contained in the reservoir, this support being retained until the member returns to its rearward position, whereupon 80 the units drop to locate the succeeding row 85 in advance of the member.

Since each complete revolution of arm or crank 17 removes a row from the reservoir, it will be clearly seen that the task of maintaining the supply of units in the reservoir 90 becomes more or less difficult owing to the number of units contained in a row—shown as ten—and the more or less restricted space provided by the length of the reservoir, the capacity conditions practically requiring that more than a single operator 95 will be required to maintain the supply within the reservoir.

To meet this condition, we prefer to employ a filling tray, such for instance, as is 100 shown in Fig. 4, in which a shallow tray 18 is employed, this tray having dimensions to receive in rows the number of units contained in a row of the reservoir and having a suitable height sufficient to permit of the 105 stacking up of a considerable number of rows. The tray is provided with a false bottom 19 against which an end of each unit is stacked, and the member is also preferably provided with a projection 18^a at its 110 lower front edge, this projection being adapted to seat in recess 12^a of plate 12^b, as shown in dotted lines in Fig. 1, the projection and recess operating to properly locate the open front of the filling tray with 115 respect to the rear open face of the reservoir, the result being that when so positioned, the false bottom can be advanced and thus locate the rows of the filling tray in their proper positions in the reservoir, it being readily understood that since the lower row is the one removed, it is necessary only to add succeeding rows at the top. 120

Since there is no expertness required in 125 stacking up the units in the filling tray, it will be readily understood that cheap labor may be employed for this particular purpose and several trays may be in use concurrently by different laborers in this stacking up operation, thus maintaining the sup- 130

ply of units in the reservoir without attempting to produce the individual stacking directly in the reservoir itself.

As will be apparent, an apparatus such as disclosed herein, when utilized in connection with work-performing apparatus adapted to operate on a multiplicity of units concurrently, provides for high capacity conditions even though the work-performing apparatus is operative at comparatively low speed. For instance, if the work-performing apparatus is operating under capacity conditions of 40 operations per minute, it will be readily understood that the actual capacity is 400 per minute, and under such conditions the question of maintenance of supply is a considerable problem because of the inability of a number of operatives to work concurrently in connection with the reservoir.

As will be readily understood, the invention is of simple character and is of few parts; therefore, the cost of construction and maintenance is relatively small. At the same time, the simplicity is such as to reduce liability of derangement, so that assurance is practically had of continuous operation with each charge properly formed and located relative to the presenting mechanism in a simple and efficient manner.

While plate 12^b and element 13 may be of any desired construction, we prefer to employ an arrangement such as is disclosed in the drawings, in which the upper face of plate 12^b is provided with a plurality of grooves 12^c which are adapted to receive complementary tongues 13^a; since the grooves extend to the top plane of the plate, it will be understood that the actual supporting surface for the units is in the form of spaced faces, thus reducing the amount of friction between the units and the plate in the advancing movement of the units; obviously, the plurality of tongues and grooves will tend to prevent any canting action of element 13 as the latter is reciprocating, and hence there is less likelihood of any binding of the element to affect the element's operation.

In addition, we prefer to provide the advance face of element 13 with a general configuration such as is indicated in Fig. 5. As shown, this face is inclined rearwardly from an intermediate point, while that portion below such point extends on different planes to form what may be termed two noses 13^b and 13^c, the latter projecting in advance of the former, but being located as a part of the tongue formation 13^a.

As will be understood, the part of element 13 which is normally active in the advancing of the unit is that located above the top plane of the tongues, and this includes portions of both of the noses. When, however, element 13 advances to a point where the

tongues begin to pass out of the advance ends of the grooves, the several noses 13^c become effective in producing the falling off action should this action have been delayed for any reason during the advancing movement. Normally the falling off action takes place without bringing the tongue portions of nose 13^c into action, but this nose, being located on a lower plane than the active portion of nose 13^b, will provide an additional element to meet any abnormal conditions presented by this change in the plane of the units, the exposing of nose 13^c bringing a face into activity on a lower plane than the face which normally acts to provide the desired result.

While we have herein shown and described a preferred way in which the invention may be carried out, it will be readily understood that the particular construction and views disclosed are more or less illustrative, and that changes or modifications therein may be found desirable or essential to meet the exigencies of use; therefore, we desire to be understood as reserving the right to make any or all such changes or modifications therein as may be found desirable or necessary in so far as the same may fall within the spirit and scope of the invention as expressed in the accompanying claims when broadly construed.

What we claim is:

1. As a means for forming and positioning a charge consisting of a plurality of similar units relative to a charge presenting mechanism, a reservoir for the charge units and having a bottom on which the face of the charge is seated, a trough for receiving the charge, said trough having an element of the presenting mechanism as its bottom, and means for delivering the charge from the reservoir to a position within the trough, and with a charge face seated on the presenting element, said means being operative to temporarily render the charge subject to gravitation to place a different face of the charge as the seated face.

2. As a means for forming and positioning a charge relative to a charge presenting mechanism and wherein each charge consists of a plurality of similar units, a reservoir for a multiplicity of charges and in which the units of the charge to be delivered are in parallelism and seated on the reservoir bottom with corresponding unit portions in advance, means for bodily advancing the units of the charge to be delivered concurrently, with relative positions of the advance portions of the units maintained, and a trough positioned to receive said advancing units, said trough including an element of the presenting mechanism as the trough bottom, the position of the trough being such as to permit the advancing units to gravitate thereinto with the advance portions of the

units positioned as the seating face of the positioned charge.

3. As a means for forming and positioning a charge relative to a charge presenting mechanism and wherein the charge comprises a plurality of charge units, a reservoir for a multiplicity of units and in which the units of the charge to be delivered are in parallelism and seated on the reservoir bottom with corresponding unit portions in advance, means for bodily advancing the units of the charge to be delivered concurrently, with relative positions of the advance portions of the units maintained, and a trough 10 positioned to receive said advancing units, said trough including an element of the presenting mechanism as the trough bottom, said trough having a wall configuration in cross-section adapted to provide a temporary support for the advanced units, the temporarily supported units being shiftable from such position by the continued advance of said advancing means.

4. As a means for forming and positioning a charge relative to a charge presenting mechanism and wherein the charge comprises a plurality of charge units, a reservoir for a multiplicity of units and in which the units of the charge to be delivered are in parallelism and seated on the reservoir bottom with corresponding unit portions in advance, means for bodily advancing the units of the charge to be delivered concurrently, with relative positions of the advance portions of the units maintained, and a trough positioned to receive said advancing units, said trough including an element of the presenting mechanism as the trough bottom, said trough being positioned relative to the reservoir bottom as to permit gravitation of the advancing units at an intermediate point in the advancing movement of said advancing means, said trough having its side walls relatively formed to 40 produce a temporary support for the gravitating units, the continuing movement of the advancing means being operative to shift the supported units from the temporarily supported position to permit completion of the gravitation movement.

5. As a means for forming and positioning a charge relative to a charge presenting mechanism and wherein the charge comprises a plurality of charge units, a reservoir for a multiplicity of units and in which the units of the charge to be delivered are in parallelism and seated on the reservoir bottom with corresponding unit portions in advance, means for bodily advancing the 55 units of the charge to be delivered concurrently, with relative positions of the advance portions of the units maintained, and a trough positioned to receive said advancing units, said trough including an element 60 of the presenting mechanism as the trough

bottom, said trough being positioned relative to the reservoir bottom as to permit gravitation of the advancing units at an intermediate point in the advancing movement of said advancing means, said trough 70 including a side wall having a substantially vertical face and an opposing wall having a face portion inclined outwardly from the vertical on cross-sections of the trough, said configurations being effective to produce a 75 temporary supporting action to the gravitating units, the continuing advance of the advancing means being operative to shift the units from such temporary supporting position and permit completion of the gravitation action.

6. As a means for forming and positioning a charge relative to a charge presenting mechanism and wherein the charge comprises a plurality of charge units, a reservoir for a multiplicity of units and in which the units of the charge to be delivered are in parallelism and seated on the reservoir bottom with corresponding unit portions in advance, means for bodily advancing the 90 units of the charge to be delivered concurrently, with relative positions of the advance portions of the units maintained, said means including a reciprocating element having the cross-sectional configuration of 95 its advance face adapted to permit free vertical movement of a unit face relative thereto, said element being adapted to advance a single row of units by a pushing action, and a trough positioned to receive 100 said advancing units and including an element of the presenting mechanism as the trough bottom, said trough being positioned to permit advancing units to gravitate thereinto.

7. As a means for forming and positioning a charge relative to a charge presenting mechanism and wherein a charge embodies a plurality of charge units, a reservoir for a multiplicity of units extending in parallel 110 rows, means for removing the units of a row concurrently as a charge and delivering the charge to the presenting mechanism, said means being operative periodically to provide a succession of charge presentings, 115 said reservoir having a partially open side with the dimensions of such open side adapted to receive a plurality of such rows concurrently, said reservoir also having a wall adjacent its bottom and forming a 120 boundary of such open side, and means for maintaining the supply of units in the reservoir, said latter means comprising a filling tray having an open side and having means complementary to said reservoir to position 125 the tray relative to the reservoir to temporarily provide a unit-receiving compartment including both elements, said filling tray also having a movable bottom adapted to permit individual location of units within 130

the tray in predetermined rows corresponding to those of the reservoir and to shift the positioned units concurrently into said reservoir.

- 5 8. In a charge positioning device, means for supporting the charge, means for transporting the charge and means for propelling the charge from the supporting to the transporting means, said propelling means having a portion contacting with the charge to propel it into an intermediate position relative to the transporting means and a second surface for finally locating the charge on said transporting means.
- 15 9. In a charge positioning device, means for supporting a charge, means for propelling the charge into operative position, said means including a propelling member having an upper face initially active to propel 20 the charge and a lower face subsequently becoming active to complete the positioning of the charge.

10. In a charge positioning device, grooved means for supporting a charge and a propelling member having tongues slidable in said grooves and adapted to propel the charge into operative position, the portion of the propelling member above said grooves operating to initially propel the charge and 30 the portion located in the grooves operating subsequently to complete the location of the charge in operative position, a magazine for a plurality of charges, and a conveyer moving in a transverse direction relative to the 35 propelling member and arranged to receive successive charges advanced by the propelling member.

11. In a charge positioning device, a magazine for holding a plurality of charges, a 40 magazine refilling device having positioning means for engaging the magazine and means carried by the refilling device for transferring charges carried thereby to the magazine.

12. A charge positioning device comprising a holder for a plurality of superposed rows, each consisting of a plurality of similar, approximately flat articles, a support for the bottom row, a pusher for removing successive bottom rows one at a time and 45 advancing the row, a conveyer moving transversely to the direction of pusher movement and arranged to receive the successively advancing rows of articles, and means coöperating with the pusher for tipping all the 50 articles of the advancing row simultaneously and delivering them on the conveyer in uniform row arrangement different from the position which they occupied in the holder.

13. A charge positioning device comprising a holder for a plurality of superposed rows each consisting of a plurality of similar articles, a support for the bottom row, a pusher for removing successive bottom 55 rows, one at a time and advancing the row,

a conveyer moving substantially at a right angle to the direction of pusher movement and arranged to receive the successive rows of articles, an inclined member arranged to support and deliver the articles in the row in a part-rotative advancing movement 70 toward the conveyer, and another guide member coöperating with the pusher to complete substantially a one quarter turn of the article row and deliver it in that position upon the conveyer.

75 14. A charge positioning device comprising a holder adapted to contain a plurality of vertically superposed rows, each consisting of a plurality of similar articles, the articles in each row being similarly arranged in an approximately flat horizontal position, a support for the bottom row, a pusher for removing successive bottom rows and advancing the rows without change of position of the articles in the advancing 80 row with relation to each other, a conveyer moving substantially at a right angle to the direction of pusher movement, and means coöperating with the pusher for delivering the row of articles to the conveyer in substantially upright, vertical position.

15. In a charge holding and feeding device, a magazine for a plurality of horizontally superposed rows of substantially flat articles, means for feeding successive rows 95 of articles from the bottom of the magazine, and filling means comprising a filling tray, a movable platen therein, the tray being adapted to hold a plurality of rows of articles in similar arrangement to the arrangement of the articles in the magazine and resting against the platen, the tray having an open face adapted to register with an opening in the magazine for the discharge of its contents simultaneously into the magazine 100 by advance movement of the platen.

16. In a charge holding and feeding device, a magazine for a plurality of horizontally superposed rows of substantially flat articles, means for feeding successive rows 110 of articles from the bottom of the magazine, and filling means comprising a filling tray, a movable platen therein, the tray being adapted to hold a plurality of rows of articles in similar arrangement to the arrangement of articles in the magazine and resting against the platen, the tray having an open face adapted to register with an opening in the magazine for the discharge of its contents simultaneously into the magazine 115 by advance movement of the platen, the magazine and tray having coöperating means to register the tray in relation to the magazine.

120 In testimony whereof we have hereunto 125 set our hands:

MATHIAS FOGDE.

LAWRENCE P. SOUTHWICK.
